ATTORNEY.

UNITED STATES PATENT OFFICE.

THOMAS A. MUSANTE, OF LOS ANGELES, CALIFORNIA.

ARTICULATOR.

Application filed January 29, 1927. Serial No. 164,562.

This invention relates to and has for a primary object the provision of an improved type of articulator, adapted for use in the making of dentures. Heretofore the articulators recognized by the dental profession as being the most accurate depended upon mechanical adjustments incorporated therein for reproducing the condyle paths, whereas my articulators are not dependent upon mechanical adjustments nor do they require mathematical computations or calculations of any kind in order to produce an exact reproduction of the condyle path. The condyle path for each individual case is so set up that accuracy is assured in the condyle action, and a correct occlusal plane necessarily follows.

Accordingly, it is an important object of my invention to provide in an articulator means for accurately setting up the dentures in such a manner that they will exactly conform to the occlusal plane of the bite-blocks and of the natural teeth.

A further object is to provide in an articulator in combination with relatively adjustable members for supporting the maxillary and mandibular casts, of means whereby an accurate record in wax or other suitable plastic material may be made from the bite-blocks so that the occlusal plane of the bite-blocks may be transferred accurately to the dentures in order that the completed dentures may as nearly as possible, conform to the original dentures of a patient.

Still other objects include the provision of a new and useful and novel design and arrangement of parts forming the structure of the articulator, and the necessary number and arrangement of the adjustments, whereby the cast supporting members may be adjusted one with respect to the other.

Other objects will appear hereinafter:

In the accompanying drawing:

Fig. 1 is a perspective view of my improved articulator, as seen from the front.

Fig. 2 is a perspective view of the adjustable maxillary cast supporting plate.

Fig. 3 is a fragmentary perspective view of the articulator as seen from the rear; and

Fig. 4 is a perspective view of the device, showing casts and dentures operatively positioned therein.

As shown in the drawings, the device in-

cludes a base B, having a horizontally disposed bottom 1, on which a horizontal plate P is mounted and arranged for adjustment longitudinally of the bottom 1. The plate P corresponds generally to the showing of a similar plate P' in Fig. 2, and is adjustable on the bottom 1 by means of a threaded stem, as at 2, which is movable through a longitudinally disposed slot, as at 3, and is held in adjusted position by means of a nut of suitable character, as at 4.

The bottom 1 of the base is provided with a forward and centrally positioned cup a, attached to or formed on the upper side of an arm 5, from the bottom 1, and similar cups b, and c are provided on arms 6 and 7 at the sides of the bottom. The axis of the cup a cuts the longitudinal center line of the bottom 1, while the axis of the cups b and c cut a transverse line at right angles to said longitudinal center line, the cups b and c being positioned substantially rearwardly of the cup a.

Below each of said cups, bosses as at 8, 8, etc., are provided on the bottom 1, which are adapted to rest on a table or bench for supporting the articulator in operative position.

At the rear of the bottom 1, the base B is provided with a transverse portion 9 having laterally projecting end portions 10 and 11, with vertical posts 12 and 13 respectively, formed thereon. The member 9 also has rests 14 and 15 on the bottom thereof, flush with the bottoms of the bosses 8 and adapted to rest upon a table or bench.

The base B is provided with an adjustable frame F at the rear, comprising a transverse member of square or rectangular cross section, as at 16, with depending hollow sleeves 17 and 18 attached thereto or formed thereon, which slidably embrace the posts 12 and 13, respectively. Said sleeves are provided with bosses 19 and 20 on their outer sides, which are internally threaded so as to receive adjusting screws 21 and 21', the inner ends of which are adapted to engage the peripheries of the posts 12 and 13, respectively, for holding the frame F in adjusted position.

The bar 16 of the frame F is in the same vertical plane as the cross bar 9 of the base B, and is adapted to slidably and adjustably

- support cups *d* and *e* on the upper side thereof, as shown. Said cups are provided with depending guide portions 22 and 22' which overlie at least three sides of the bar 16, and slide thereon. The cups are held in adjusted positions by means of sets screws 23 and 23', respectively, which are threaded into the guides of the cups, and the inner ends of which engage one of the sides of the bar 16.
- Substantially above the base, and mounted on the frame F for universal movement with respect to said base, I provide an upper member or top D, with a web 24 having a central front arm 25, and laterally projecting arms 26 and 27. Said arms carry, respectively, downwardly extended bearings 28, 29 and 30, which are adapted to adjustably and slidably receive guide pins G, *g* and *g'*, respectively. Said pins are held in selected positions by means of set screws 31, 32 and 33, respectively; which extend through the bearings of the pins and engage the peripheries of said pins. The top member D has a rearwardly extending portion 34 which is attached to or formed on a transverse member 35 in the vertical plane of the member 16, and carrying on its end portions adjustable sleeves 36 and 36'. Member 35 is preferably of square rectangular cross section, and the sleeves 36 are correspondingly formed so that they may slide on the member 35, but may not be rotated thereon. Said sleeves are held in selected positions by means of set screws 37 and 37' and at their outer ends are provided with depending pins *f* and *f'*, which are positioned approximately centrally of the cups *d* and *e*. The top member D is attached to and supported on the frame F in the following manner. The bar 16 has a centrally formed upstanding portion 38 which is provided with horizontally formed portions 39 and 39', on the opposite sides of the portion 38 and in the plane of the member 16. Coil springs S and S' serve to connect the members D and F in adjustable relation. Said springs S and S' are provided, respectively, with bent inner end portions 40 and 41 which are extended through the inner portions of extensions 39 and 39', while the outer end portions 42 and 43 of said springs are bent inwardly and thence upwardly through perforations in the member D, the ends of said bent portions overlying the top of the member D, as shown in Fig. 3.
- The springs S and S' are coiled around the extensions 39 and 39', and being attached thereto serve to hold the top D resiliently hinged to the frame F for universal movement, the tension of the spring serving to maintain the member D and associated parts in a central position with respect to the base B. The record cups *d* and *e* are positioned in the condyle plane and have horizontally alined pins 45 and 46 extended outwardly therefrom at positions corresponding to the temporal mandibular joint, from which all measurements in the articulator are taken and all adjustments are made.
- As shown in Fig. 4 the plate P on base B is adapted to support a mandibular cast as at M, which has fixed thereto the lower or mandibular denture H. Likewise, the plate P' attached to the member D is adapted to support the maxillary cast M' which has fixed thereto the maxillary denture H', the casts M and M' being made of plaster or being formed so that the plaster will fill and overlie a plurality of openings as at 47, 47 in Figs. 2 and 4, for holding the casts fixedly on the supporting plates.
- The record cups *a*, *b*, *c*, *d* and *e* which are mounted in the manner herein described on the base B, are adapted to be filled with a wax or other suitable plastic element, as at W. The cups are filled with the wax to the approximate plane of the upper edges, and is then moulded in the cups so as to provide concave upper faces, as at 49, 49, etc.
- It will be observed that the incisal guide pin G is positioned on the member D so as to be normally central with respect to the incisal record cup *a*, and the lateral occlusal guide pins *g* and *g'* are mounted centrally on member D with respect to the cups *d* and *e* of the member B. When the members of the articulator are properly positioned with respect to each other, the condyle path guide pins *f* and *f'* should be central with respect to the record cups *d* and *e*, respectively. The pins 45 and 46 extended from the cups *d* and *e*, respectively, are adapted to pivotally support the usual face-bow attachment by means of which the bite-blocks are transferred, in proper position, from the patient's mouth to the articulator, so as to receive and mount the maxillary or mandibular casts on models from which mounted casts and bite-blocks the records of the condyle path is transferred to the articulator.
- The guide pins G, *g* and *g'* are provided on their lower ends with enlargements 50, 50, etc., having their lower ends substantially rounded, as indicated, for engagement with the upper surface of the wax inlays in the record cups, so that the pins may be caused to move easily over the upper faces of said inlays in making a record, as hereinafter described.
- In operation, the bite-blocks having been previously made and the occlusal inclined plane established thereon by proper technique, not material to this invention, and the same having been attached to the usual face bow, the bite-blocks are then mounted on casts, as at M and M' and attached to the plates P and P', respectively, of the articulator. The approximate position of the oc-

clusal plane is established in the articulator in the original set up, by the several adjustments so as to properly position this plane with respect to the temporal mandibular joints, as defined by the pins 45 and 46.

Plates P and P' are adjustable so as to indicate protrusive or retrusive relations between the bite-blocks. The sleeves 36 and 36' are adjustable laterally to properly position the face bow attachment, and the guide pins G, g and g' are adjusted in their bearings so that when the bite-blocks are in a position of centric occlusion, the record making portions 50 thereof will rest upon the upper concave faces 49 of the wax inlays W in the record cups. In this position all of the adjustments are set up so as to retain the relative positions of the casts M and M' which hold the bite-blocks in centric occlusion.

Thereafter, the wax inlays W are heated so as to soften the same to a sufficient extent that they will be marked by the portions 50 of the guide pins when the upper member D is moved universally with the bite-blocks in proper occlusion. The portions 50 thus serve to indent the concave faces of the wax inlays W laterally, longitudinally, circulatory and vertically, in exact conformity to the occlusal inclined plane of the bite-blocks, and may be said to transfer the exact conditions of occlusion to the record cups.

It will be understood in this connection that all of the record cups a, b, c, d and e cooperate to produce this record, the axis of the maxillary support D being substantially in the condyle path, that is, coincident with the axes of the pins 45 and 46. Thus, any irregularity or peculiarity in the occlusal inclined plane is at once indicated on one or more of the record cups.

After the completion of the record from the bite-blocks, the wax inlays are allowed to again harden, preparatory to a transfer of the record from the inlays to the dentures H and H'. In order to effect the articulation of the dentures the bite-blocks are removed from the casts and base plates, and placed on the casts upon which the dentures are set up. In my technique I allow the lower bite-block to remain in position on its cast and set up the upper denture, using the lower bite-block as a guide. I first adapt a base plate to the upper cast and set up the teeth thereon, allowing the cusps to rest on the lower bite-block, the surface of which is already in an approximate plane. These casts are not removed from the articulator at any time until the dentures are ready for the flasking operation. Thus the dentures H and H' are inserted in the same positions on the members B and D in which the bite-blocks casts were held, so that the occlusal inclined plane of the dentures will be exactly

in the same position with respect to the temporomandibular joint, as in the case of the bite-blocks.

The incisal guide pin G and the lateral occlusion pins g and g', and also the condyle path guides having been retained in their original record making positions when the dentures H and H' are properly positioned as shown in Fig. 4, the movement of the guide pins in the record grooves of the wax inlays W will indicate the correct meshing of the teeth in the dentures H and H', and necessary changes to be made in said dentures in order that the occlusal inclined plane already established may be transferred exactly to the dentures for effecting a permanent coordination therebetween corresponding to the exact conditions prevailing in the patient.

The technique from here on is substantially the same as now in vogue, and necessarily includes the adjusting and setting of the teeth in the dentures, the proper meshing thereof, adjusting the dentures in the casts, and other adjustments which tend to produce the proper relationship between the dentures and the maintainance of the inclined plane thereof as established in the record.

It will be observed by reference to the description and drawings of my device, that the interconnection between the members B and D is such as to provide a complete universality of movement of the member D. Said member may be tilted laterally, backwardly and forwardly, the same may be oscillated in any direction, and the tension of the springs S and S' serve to maintain the normal relationship between the two members and to restore the member D to such normal relationship when the same is moved.

It will be apparent to those skilled in the art that I may modify my invention within the scope of the appended claims without departing from the spirit thereof.

What I claim is:

1. An articulator for the purpose described, comprising relatively movable mandibular and maxillary denture supporting members, means including a plurality of plastic recording elements positioned at points forwardly and on opposite sides of the set of dentures on one of said members, and guides on the other of said members corresponding in positions to and adapted for contact with the plastic elements, for the purpose described.

2. An articulator comprising a mandibular denture supporting member having a plurality of plastic record making elements supported at the front and sides thereon, a maxillary denture supporting member movable with respect to said other member, and provided with guides corresponding in number and positions to and arranged for contact

with said plastic elements for marking the plastic elements to correspond to the occlusal inclined plane of the dentures.

3. An articulator including a base for supporting dentures thereon, a plurality of cups on the base radially arranged with respect to and positioned forwardly, laterally and rearwardly of said denture, a relatively movable member above said base for supporting another denture in occlusion with the first denture, a plurality of guide members vertically alined with said cups and supported on said movable member, and plastic elements carried in said cups for contact with said guide members, whereby when the upper member is moved with said dentures in occlusion, corresponding markings will be made in said plastic material by means of said guide member.
4. An articulator comprising a stationary base having a plurality of fixed cups, at the front and sides thereof, a top member resiliently connected with said base for universal movement, recording elements carried in said cups, and guide pins adjustably carried on said top for engagement with and for marking on said recording elements to indicate the movement of said top.
5. An articulator comprising a base having a plurality of fixed record cups thereon, below the occlusal plane, and a pair of adjustable record cups transversely alined in the condyle path and above the occlusal plane, said cups having recording elements therein, a top resiliently connected to said base and provided with members cooperating with all of said record cups for indicating the movement of the top with respect to the base.
6. An articulator comprising a base, a frame vertically adjustable on said base, a plurality of record cups in fixed positions on the base, a pair of record cups adjustable vertically and horizontally on the base, a top resiliently connected to said frame for universal movement with respect to the base, and means on the top cooperating with said record cups for recording the movement of the top with respect to the base, for the purpose described.
7. An articulator comprising a stationary base having means for supporting a denture thereon, a frame vertically adjustable on the rear of said base, a top yieldably mounted on said frame arranged for universal movement with respect thereto, and pro-
- vided with means for supporting a denture thereon, a pair of cups having recording elements therein adjustable with said frame with respect to said base, and laterally on said frame, and transversely alined in a condyle path, and a pair of marking elements or guide members laterally adjustable on said top and cooperating with and for marking the limits of occlusion of said dentures on said recording elements.
8. An articulator as characterized in claim 7 including a plurality of cups fixed to said base and having recording elements therein, and arranged at points forwardly and on opposite sides of said dentures, and adjustable guide pins supported on said top in vertical alinement with said cups for recording the limits of occlusion at points below the occlusal plane of the dentures.
9. An articulator comprising a stationary base having a plate centrally mounted thereon for supporting a mandibular denture, a plurality of cups forwardly and laterally of said plate for holding a plastic recording element, a pair of transversely alined posts vertically extended from the rear of said base, a frame vertically adjustable on said posts, a top yieldably supported on said frame and provided with a plate for supporting a maxillary denture in occlusion with said mandibular denture, a pair of record cups laterally adjustable on said frame above the plane of occlusion of said dentures for supporting a plastic recording element, a plurality of vertically adjustable guide pins supported on said top in alinement with said fixed recording elements, and a pair of laterally adjustable guide pins supported on said top for engagement with said adjustable recording elements, for the purpose described.
10. An articulator comprising a stationary base and a movable top arranged, respectively, for supporting mandibular and maxillary dentures in occluding positions, means for yieldably supporting said top on said base, and a pair of transversely alined marking elements and recording elements laterally adjustable in the condyle path for recording the limits of occlusion of said dentures.
11. An articulator as characterized in claim 10 including means for vertically adjusting said top and said marking elements.

THOMAS A. MUSANTE.
